CLAIM

The ornamental design for surge protector for a facsimile machine, as shown and described.

DESCRIPTION

FIG. 1 is a perspective view of a surge protector for a facsimile machine showing our new design;

FIG. 2 is a right side elevational view of a surge protector for a facsimile machine showing our new design on an enlarged scale, the left side elevational view being a mirror image;

FIG. 3 is a top plan view thereof;

FIG. 4 is a bottom plan view thereof;

FIG. 5 is a front elevational view thereof;

FIG. 6 is a rear elevational view thereof.

FIG. 1
